UNITED STATES PATENT OFFICE.

JEROME R. GEORGE, OF WORCESTER, MASSACHUSETTS, ASSIGNOR TO MORGAN CONSTRUCTION COMPANY, OF WORCESTER, MASSACHUSETTS, A CORPORATION OF MASSACHUSETTS.

ROLLING-MILL.

No. 926,863.

Specification of Letters Patent.

Patented July 6, 1909.

Application filed September 20, 1905. Serial No. 279,256.

To all whom it may concern:

Be it known that I, JEROME R. GEORGE, a citizen of the United States, residing at Worcester, in the county of Worcester and 5 Commonwealth of Massachusetts, have invented a new and useful Improvement in Rolling-Mills, of which the following is a specification, accompanied by drawings forming a part of the same, in which—

10 Figure 1 represents a plan view of a rolling mill embodying my invention. Fig. 2 is an end elevation of the same, and Fig. 3 is a cross section on line 3—3, Fig. 1, of the curved repeater 19.

15 Similar reference letters and figures refer to similar parts in the different views.

My present invention relates to that class 20 of rolling mills known as "continuous" and it has for its object to increase the efficiency 25 of a rolling mill of this class, both as regards the amount and character of product, and it consists in the construction and arrangement of parts as hereinafter described and set forth in the annexed claims.

25 Referring to the accompanying drawings A denotes an ingot or billet heating furnace, 1, 2, 3, 4, 5 and 6 denote a series of rolls arranged in alinement for the continuous rolling of the ingot or billet and forming a continuous train similar to that now employed 30 in mills of this class and driven from a driving shaft 7 by a series of bevel gears arranged to give the relative circumferential speed to each succeeding pair of rolls to provide for 35 the elongation of the metal as it is successively compressed between the rolls, and delivering the rod to a repeater 8 having a semicircular bend 9 by which the direction of 40 the rod is reversed and delivered from the mouth 10 of the repeater upon an elevated floor 11. The rod is then returned upon itself and passed through a series of rolls 12 45 12^a forming a loop on the floor 11 which varies in size according to the overfeed of the metal as indicated by the broken lines 13, 14.

The rod as it leaves the series of rolls 12, 12^a, is delivered to a second semicircular repeater 15 which reverses the movement of the rod and delivers it again upon the elevated floor 50 11, where it is conducted through a pair of rolls 16 and 17 and delivered to a third semicircular repeater 18 by which the movement

of the rod is again reversed and the rod is delivered to a curved repeater 19 by which the rod is conducted to the rolls 20, 21. The 55 short semicircular repeater 19 has the central portion 22 of its outer wall beveled to enable the loop caused by the overfeed of the rod to be pushed out of the repeater on to the floor 11. The broken lines 23 and 24 represent 60 the position of loops on the floor 11 as the rod is delivered from the repeaters 15 and 18 respectively. From the rolls 21 the rod is taken to any one of the reeling mechanisms 65 25.

My continuous mill as above described comprises a multiplicity of sections, in the present instance four in number, and between each section the overfeed of the rod is enabled to expend itself in unconfined loops 70 upon the floor 11, several loops being all formed upon the same floor and upon the same side of the several sections, leaving the opposite side of the sections entirely free.

The series of rolls 1 to 6, and series of rolls 75 12, 12^a I term reducing sections, and the series of rolls 16, 17, and 20, 21, I term finishing sections. I arrange to drive the first pair of rolls in each of the finishing sections at the same speed as the last pair of rolls in the 80 next preceding section, for example, the pair of rolls 16 in the first finishing section is coupled to and driven at the same speed as the last pair of rolls 12^a in the preceding reducing section, and the first pair of rolls 20 85 in the second finishing section is coupled to and driven at the same speed as the last pair of rolls 17 in the preceding finishing section. The pair of rolls 16 are driven through intermittent connecting mechanism by a belt 26 90 from an engine or other source of power, not shown, and the pairs of rolls 17 and 20 are driven by belts 27 and 28 at a higher rate of speed, and the pair of rolls 21 are driven through the same belts, but at a still higher 95 speed, the driven pulley 29 being smaller than the driven pulley 30, which drive respectively the shafts 31 and 32. The last pairs of rolls 17 and 21 in each of the finishing sections is, however, smaller in diameter 100 than the initial pairs of rolls 16 and 20 in each finishing section, the reduction in diameter of these rolls being compensated for by their increased angular velocity, so that the

circumferential speed of rolls 17 and 21 remains greater than that of rolls 16 and 20. The reduction in diameter of the last pairs of finishing rolls in each of the finishing sections enables the desired size of the rod to be secured with greater accuracy. The circumferential speed of the last pair of rolls in each finishing section is slightly greater than the circumferential speed of the first pair of rolls 10 in the same finishing section, due to the elongation of the metal, so that the second pair of rolls will take up the metal as fast as delivered by the first pair of rolls in the section, thereby preventing a loop being formed by 15 the overfeed of the first pair of rolls. When the entire number of passes in the finishing mill are not required for the reduction of the metal, a portion of the rolls can be omitted, for example, pairs of rolls 12^a, 17 and 21, or 20 either of them, can be separated so they will not act on the metal passing through the mill, leaving the entire reduction to be accomplished by the pairs of rolls 12, 16 and 20.

What I claim as my invention and desire 25 to secure by Letters Patent is:—

1. In a continuous rolling mill, the combination of a series of pairs of rolls forming the reducing portion of the mill, said rolls being arranged in two separate sections, with the 30 second section out of alinement with the first section, and a semicircular repeater by which a rod is conducted from said first section and around the delivery end of said second section, and means for supporting the 35 overfeed as the rod is taken from said repeater to the receiving end of said section.

2. In a continuous rolling mill, the combination with two series of pairs of rolls placed out of alinement with each other, of a repeater by which the metal is conducted from the delivery end of the first series around the delivery end of the second series, and a supporting floor for the overfeed at the receiving end of the second series.

45 3. In a continuous rolling mill, the combination with a series of reducing rolls arranged in pairs for the consecutive reduction of a rod, of a finishing section comprising two pairs of rolls and a semicircular repeater leading from the last pair of rolls in said series of reducing rolls around the last pair of rolls in said finishing section.

4. In a continuous rolling mill, the combination of a series of rolls arranged in separate 55 sections, with the rolls in each of said sections out of alinement with the remaining sections, a series of semicircular repeaters leading from the delivery pair of rolls of one section around the delivery pair of rolls of the 60 next succeeding section, and a floor for the support of the overfeed in front of the receiving pairs of rolls in each section.

5. In a rolling mill, the combination with a series of pairs of reducing rolls for the con-

secutive reduction of a rod, of finishing rolls 65 with their passes out of alinement with the line of passes in said series of reducing rolls but parallel therewith, and means for conducting a rod from the reducing to the finishing rolls, and around said finishing rolls, 70 whereby the movement of the rod is in the same direction, through both of said finishing and said reducing rolls.

6. In a continuous rolling mill, the combination of a series of pairs of rolls for the consecutive reduction of a rod moving in the same direction through each pair of rolls, 75 said pairs of rolls arranged in sections, and means for conducting a rod from the delivery end of one section around the delivery end of 80 the next succeeding section to enter on the opposite side of a pair of rolls in said succeeding section.

7. In a continuous rolling mill, the combination of a series of pairs of rolls for the consecutive reduction of a rod, said series being arranged in parallel sections with their axes 85 out of alinement with each other, means for conducting a rod from the delivery end of one section around the next succeeding section to the receiving pair of rolls therein, whereby the movement of the rod is in the same direction through the several sections, and means for supporting the overfeed between the sections.

95 8. In a continuous rolling mill, the combination of a series of rolls for the consecutive reduction of a rod arranged in sections, out of alinement with each other, semicircular repeaters leading from the delivery pair of 100 rolls in one section around the delivery pair of rolls in the next succeeding section, whereby the movement of the rod is reversed, means for supporting a semicircular loop of the rod between said repeaters and the receiving pair of rolls in said sections.

9. In a continuous rolling mill, the combination of a series of finishing rolls arranged in sections, comprising at least two pairs of rolls in each section, means for rotating the 110 first pair of rolls in each section at the same circumferential speed as the last pair of rolls in the preceding section, but at a less circumferential speed than the last pair of rolls in the same section.

115 10. In a continuous rolling mill, the combination with a series of finishing rolls arranged in sections, comprising at least two pairs of rolls in each section with the first pair of rolls coupled to the last pair of rolls in 120 the next preceding sections, and means for rotating each succeeding coupled pairs of rolls at an increased velocity.

11. In a continuous rolling mill, the combination with a series of rolls for the consecutive reduction of a rod, and comprising successive sections of finishing rolls having at 125 least two pairs of rolls in each section, with

the first pair of rolls in each section coupled to the last pair of rolls in the next preceding section, means for driving the successive coupled pairs of rolls at different angular velocities, and means for conducting a rod from the delivery end of one section around the delivery end of the next succeeding sec-

tion, whereby the movement of the rod is reversed.

Dated this 18th day of September 1905.
JEROME R. GEORGE.
